UNITED STATES PATENT OFFICE.

CORNELIS J. H. PENNING, OF UMFOLOZI RIVER, ZULULAND, SOUTH AFRICA.

WIRE-STRETCHING DEVICE.

1,292,867.

Specification of Letters Patent. Patented Jan. 28, 1919.

Application filed October 29, 1917. Serial No. 199,159.

To all whom it may concern:

Be it known that I, CORNELIS JOANNES HUGO PENNING, a subject of Her Majesty the Queen of Holland, and resident of Umfolozi River, Zululand, South Africa, have invented certain new and useful Improvements in Wire-Stretching Devices, of which the following is a specification.

This invention relates to improvements in wire stretching and wire connecting devices applicable for use in connection with fencing wires, stay wires, telephone, telegraph, or other electrical wires and for all purposes where a wire, rope or the like requires stretching or tightening between two points.

The primary object of this invention is to provide a stretching device which can be placed on any part of a wire, rope, or the like requiring stretching, after this wire rope or such like has been fixed between two points. Another object is to provide a stretching arrangement, which combines great strength with lightness and can be easily manipulated to highly tension very stiff wires such as steel piano wires, barbed wire or wire ropes.

A further object is to provide an arrangement whereby it is possible to connect two wires, or repair quickly a broken fencewire, stay wire, or the like.

A still further object is to so construct the stretcher that it will be self locking on the wire.

According to this invention the wire stretching device comprises a guide or frame for engaging the wire and a stretcher adapted to engage the wire and be turned or rotated about the said guide to stretch the wire or the like, the said guide permitting a high tension to be obtained on the wire without the stretcher side-slipping or twisting out of alignment therewith.

I will now describe my invention with reference to the accompanying drawings in which:

Figure 1 is an elevation; Fig. 2 is a plan and Fig. 3 is a sectional elevation of one form of guide or frame constructed according to this invention.

Fig. 4 is an elevation and Fig. 5 is a plan of one form of stretcher.

Figs. 6 and 7 are side and end elevations respectively of a modified form of stretcher for heavy wires.

Figs. 8 and 9 are side and end elevations respectively of a modified form of guide or

frame for permanently attaching to the wire;

Fig. 10 is a diagram showing two guides for securing an inserted length of wire; 60

Fig. 11 is a view of guide in halves for heavy wires or steel ropes.

Referring first to Figs. 1 to 3, a guide or frame *a* is provided, with holes or slits through which the wire *b*, or rope, is guided. 65 The shape of this guide or frame is optional, and it may be made of one or more pieces. In this guide or frame an axial opening or bearing *d* is provided in which the actual stretching device *e* is mounted and turned. 70 Once the stretcher *e* is in place, and the wire *b* or rope taut, the guide or frame *a* is removed.

The guide or frame *a* may comprise a cylindrical handle portion *f* to be gripped in 75 one hand, which handle portion is of cup form and recessed at one end to form a bearing *d* for the winding pin or drum *g*, and diametrically opposed slots to guide the wire or rope. These slots *c* may be straight or 80 axial in direction or bayonet joint shaped as shown at *c'* so as to give a better guidance.

The actual stretching device *e*, preferably formed in one piece, consists of a bar bent at one end to form a winding pin or drum *g*, 85 provided with a transverse hole or slot *h*, or other engaging means to receive the wire *b*; a lever or crank *e* provided at one end of this pin or drum *g*; and a locking arrangement or catch *i* provided at the other end of this 90 lever *e*. The winding end *g* and the catch end *i* are both preferably disposed at right angles to the main portion of the stretcher and lie in the same plane with each other, as shown in Figs. 4 and 5. In these figures a 95 notch or sawcut is provided at the end *i* into which the wire is adapted to be inserted to hold the stretcher in position.

The winding pin or drum *g* of the stretching device is adapted to be revolved in the 100 opening or bearing *d* of the guide *a*, and to shorten the wire *b* or rope by winding it up when the lever *e* is turned. When the required tension is reached, the locking arrangement *i* serves to lock the winding drum 105 in place by resting against the taut wire *b* or rope.

In using this stretching device, the guide or frame *a* is taken in one hand and placed on the slack wire *b*, the wire passing through 110 the bayonet slot *c'* therein and over the bearing opening *d*. The drum or pin *g* of the

stretching device *e* is then inserted in the bearing *d*, the wire or rope *b* passing through the slit *h* in the drum *g*. The stretching device *e* is then turned around so that the wire or rope *b* is wound on the drum *g*, and when the required tension has been attained the lever *e* is then locked on the wire *b* by the said wire engaging in the notch *i*. The guide or frame *a* is then removed and the stretcher *e* 5 remains on the wire *b*. In practice it has been found that the slit *h* is automatically closed by the wire coiling around the drum *g*. If the wire requires further tightening, the guide or frame *a* can be replaced, and the 10 drum *g* further wound up.

To connect two wires the two ends are passed through the guide and the stretcher slipped over both wires and applied as before. When the stretcher is in place the 15 guide can be removed.

In a modified construction of the invention as shown in Figs. 6 and 7 the stretching device *e* may be formed as a longitudinal bar of metal carrying the winding 20 drum *g* at one end, which latter is formed with a slot *h* whose edges may be rounded off. Arranged at the other end of the bar is the locking device *i* preferably consisting of a small hook *j* which grips over the wire 25 and which can be closed or bent around the wire for a fixture.

If desired holes may be provided in the guide or drum in the place of slits to take the wire or rope but in this case the guide 30 or drum must be slipped onto the wire or rope before this is fastened between the fixed points and the guide must remain in place if provided with holes instead of with slits. In Figs. 8 and 9 the guide *a* is in 35 the form of a tube provided with two diametrically opposed holes *d* in the sides so stamped out as to form a double bearing for the stretcher *e*. This guide can be stamped from sheet metal. These guides 40 are especially suitable for repair work to wires as shown in Fig. 10. The guides can be held, when turning the stretcher, by a pair of pincers.

The guide when intended for use with 45 heavy wire ropes may be made as shown in Fig. 11 in two halves in the form of an elongated box *l* having slots *c* at the two opposite ends to provide guides for the wire *b* and slots *d* at the opposite sides to form 50 a double bearing for the winding drum. The halves of the box *l* are adapted to slide one in the other to hold the wire *b* and are secured by pins *m* passing through holes *n* in each of the halves of the box.

60 What I claim is:—

1. In a device of the character described, a frame having wire guiding means therein, a stretcher mounted in and rotatable about the frame, wire gripping means 65 formed on one end of the stretcher and en-

gaging said wire between said guiding means, and means formed on the other end thereof to engage with the tensioned wire and hold the stretcher on the wire independently of the frame. 70

2. In a device of the character described, a frame having a handle by which it may be manually held, and provided with means for guiding a wire loosely therethrough, a stretcher consisting of a bar having a winding pin at one end and a catch remote from said pin, said frame having a bearing opening at right angles to said guiding means, said opening being adapted to detachably receive the winding pin inserted in the path 75 of the wire, the latter being wound upon the pin when the stretcher is revolved, said catch engaging the tensioned wire and holding the stretcher from unwinding. 80

3. In a device of the character described, 85 a frame having spaced wire guiding slots therein for the passage of a wire loosely therethrough, a stretcher mounted in and rotatable about the frame, a wire gripping pin on the inner end of the stretcher, and 90 engaging the said wire between said slots, and means formed on the outer end of the stretcher to catch the wire and hold the stretcher on the wire when the frame has 95 been removed.

4. In a device of the character described, a frame having a handle by which it may be manually held and having means for guiding the wire loosely therethrough, a stretcher mounted in and rotatable about the frame, said stretcher acting as a combined crank and winding drum, a wire gripping pin at the bearing end of the stretcher, and a catch at the other end, said catch being adapted to engage the wire and hold 100 the stretcher on the wire when the frame has been removed from the wire. 105

5. In a device of the character described, a frame having wire guiding slots, a bearing provided in said frame between the 110 slots, a stretcher rotatable in the bearing at one of its ends, said stretcher being in the form of a crank, a wire engaging means on the bearing end of the stretcher, on which end the wire is wound and an independent 115 wire engaging means on the other end, the said ends being both offset at right angles to the main part of the stretcher, and the said independent wire engaging means being adapted to catch the wire and hold the 120 stretcher on the wire when the frame has been removed from the wire.

6. In a device of the character described, a frame having a handle and wire guiding means at the end of the handle, a bearing 125 provided in said frame at right angles to said guiding means, a stretcher rotatable in said bearing at one of its ends, said stretcher acting as a combined crank and winding drum, a wire engaging means on the bearing 130

end of the stretcher, and a catch on the other end, the wire guiding means permitting the removal of the frame from the wire without disturbing the stretcher, the catch being adapted to engage the wire and hold the stretcher on the wire under the influence of the wire tension when the frame has been removed from the wire.

7. In a device of the character described, 13 a frame having spaced wire guiding means and a bearing provided in said frame between said guiding means, a stretcher hav-

ing one end rotatable in said bearing, said stretcher acting as a combined crank and winding drum, a wire engaging slit on the 15 bearing end of the stretcher, and a catch provided on the other end and adapted to engage the wire and hold the stretcher on the wire under the influence of the wire tension when the frame has been removed from 20 the wire.

In testimony whereof I have hereunto signed my name.

C. J. H. PENNING.
